Patented Mar. 2, 1976

239,029

MAGNETIC STRIPE CARD READER OR THE LIKE

Ronald I. Conway, Port Ewen, Robert V. Jones, Kingston,
John J. Natoli, Woodstock, and John V. Stram, Pough-
keepsie, N.Y., assignors to International Business
Machines Corp., Armonk, N.Y.

Filed July 16, 1973, Ser. No. 379,879

Term of patent 14 years

Int. Cl. D14—02

U.S. Cl. D26—5 C

FIG. 1

FIG. 2

FIG. 3

FIG. 1 is a frontal perspective view of a magnetic stripe card reader or the like, showing our design.

FIG. 2 is a front elevational view thereof.

FIG. 3 is a rear perspective view thereof.

The bottom surface of the design is plain.

We claim:

The ornamental design for a magnetic stripe card reader or the like, substantially as shown and described.
